INVENTOR,

VLADIMIR J. POLYDOROFF,
BY
Thomas G. Keward,

ATTORNEY.

UNITED STATES PATENT OFFICE.

VLADIMIR J. POLYDOROFF, OF CHICAGO, ILLINOIS, ASSIGNOR TO JOHNSON-WILLIAM-SON LABORATORIES, INC., OF CHICAGO, ILLINOIS, A CORPORATION OF ILLINOIS.

RADIOFREQUENCY AMPLIFYING CIRCUITS.

Application filed February 5, 1927. Serial No. 166,107.

The invention relates to radio-frequency amplifying circuits wherein three-electrode tubes are used as amplifiers, and, generically considered, consists of means for preventing undesirable oscillations in said circuits.

It is a well-known fact that radio-frequency amplifiers of the so-called tuned radio-frequency type, wherein the tuning circuits constitute parts of a grid circuit, are subject to feedback currents, which currents, especially in multi-stage amplifiers, produce undesirable oscillations. Said oscillations combine with and distort the incoming signals, and, owing to regeneration, produce noises, and sometimes the incoming signal is entirely wiped out.

These undesirable effects in existing circuits are chiefly due to the capacity effect between two electrodes of the commonly used three-electrode tube, wherein the plate circuits feed back currents to the grid circuits. In the multi-stage amplifier, in addition, stray fields between the transformers and also electrostatic fields between condensers, increase the magnitude of undesired oscillations.

The invention has for its object the production of a new tuning device and circuits therefore, whereby undesirable oscillations in radio-frequency circuits are avoided.

Another object of this invention is to eliminate so-called body capacity effects, which are especially noticeable in radio receivers using non-grounded loop antennæ.

The invention will be better understood by referring to the attached drawings, in which—

Figure 1 is a circuit diagram showing the invention as applied to one stage of radio amplification;

Figure 2 shows a modification of the invention, and

Figure 3 shows the modification appearing in Figure 2, in an apparatus having multi-stage circuits.

In Figure 1 is shown a tuning circuit comprising an inductive coil 1 and variable capacity 2. The circuit is tuned in accordance with the incoming frequency, and the coil 1 receives energy from an outside source such as a broadcasting station or a coil 12, assuming that coil 1 is inductively coupled to coil 12.

At any given instant the condenser 2 is charged so that a difference of potential V between its two electrodes, 3 and 4, is equal to

the difference of potential generated on the coil 1, and, if the lower plate 4 is grounded and has a consequent zero potential, as shown by dotted ground line 5^a the upper plate 3 will have a potential V.

Between the two plate-electrodes of the condenser a third electrode 6 is interposed. This electrode may be a fine mesh of wire of any conductive substance, or a perforated plate of similar material. This third electrode should have no effect on the performance of the condenser, except for slight variations in capacity value, and, if grounded, as shown by a solid line 5, and both main plates, 3 and 4, are left open to the ground, said third electrode becomes an electrostatic screen. The potential difference remains V, but the distribution of the potential becomes different. The upper plate will have potential +v₁, the lower plate -v₂, so that the formula for the total potential difference is:

$$+v_1 - (-v_2) = V$$

One potential factor, +v₁, is applied to the grid circuit of the tube by connecting the grid electrode 7 to upper plate 3 and the filament 8 to the third electrode 6, while the other potential factor, -v₂, is applied to the plate electrode 9 of the tube through a small adjustable condenser 10, thus establishing a tuned circuit which is adapted to react upon both the grid and the plate circuit of a three-electrode tube.

The capacity of condenser 10 can be so adjusted that it will satisfy the equation

$$\frac{C_b}{C_p} = \frac{V_1}{V_2} \quad 90$$

where C_b is the capacity value of condenser 10, C_p capacity between plate and grid, and v₁, v₂ are the values previously defined. In this case, feedback currents originating in the plate circuit 11 will leak between elements 9 and 7 to the upper plate 3, and through the condenser 10 to the lower plate 4 and return by the electrostatic screen 6 to filament 8, thereby establishing a potential difference between each plate of condenser 2 and the electrostatic screen of such magnitude that V_{1p} + V_{2p} = 0, i. e., V_{1p} = -V_{2p}, where V_{1p} and V_{2p} are, respectively, voltage drops due to plate feedback currents.

It is evident that, if the main tuning condenser is not affected by potential variations due to feedback currents, the winding at

tached to said condenser will likewise be unaffected by the potential variations due to the feedback currents.

I have found that a substitute for the electrostatic screen, hereinbefore described, may be a grounded shield having zero potential, insulated from the variable condenser, made of any conductive material, and completely enclosing both tuning elements of said variable condenser. Such a shield is shown in Figure 2.

It is a known fact that the electrostatic field established between the two plates of a condenser is partly dissipated and radiated therefrom, producing so-called "radiation losses." When, however, an electrostatic shield is used, the radiation field will affect the electrostatic shield, and, by induction and on account of zero-shield potential, change the distribution of potential on the condenser plates in the same manner as the electrostatic screen placed in the middle of the condenser.

In Figure 2, parts 1 to 10, inclusive, are identical with the elements designated by the same indices in Figure 1. However, for the electrostatic screen is substituted a grounded electrostatic shield 13. This shield 13 is insulated from the variable capacity 2, and, because of its relation to said variable capacity, will change the distribution of the potential on the plates 3 and 4, in the same manner as the electrostatic screen 6, shown in Figure 1.

Figure 3 shows a multi-stage set, in which a shield, such as is shown in Figure 2, is employed in each of its stages of radio frequency. It should be noted that for proper operation of this set the polarities of two adjacent windings, 11 and 14, of a transformer 15, should be reversed.

The electrostatic shield, being grounded or of zero potential, does not affect tuning of the elements of the circuit, and the approach of an operator's hand to the receiver will not affect such tuning because the operator's potential is substantially the same as that of said shield. This fact is of special value if a loop receiver having no ground connection is used, since the approach of an operator's capacity introduces no additional aerial to the circuit. In fact, in the type of circuit just described, the electrostatic shield can be actually grounded to the earth without impairing the directional qualities of the loop reception.

The drawings further show, antennæ 16, filament battery 17 with its regulating resistance 18 and plate battery 19, necessary for the operation of the circuit. It will be understood that when a loop antennæ is preferred the connection to the actual ground is not essential, as the metal frame of the apparatus will serve as a ground.

Having thus described my invention, what I claim is:

1. A radio apparatus provided with an oscillatory circuit including a condenser, and

an element electrostatically associated with said condenser, two of the condenser plates and said element being connected with the control electrode, the anode and the cathode of the radio-amplifying tube, and means to regulate feed-back currents in said circuit.

2. A radio-frequency amplifier including a thermionic tube, an oscillatory circuit comprising a coil and a condenser, and a grounded element electrostatically coupled to said condenser, said element being connected to the cathode of said tube, and the plates of said condenser being connected to the grid and plate of said tube.

3. A radio circuit including a thermionic tube, a condenser having associated therewith electrostatic means comprising an element electrostatically related to plates of said condenser, and another adjustable element, said elements being employed for balancing feed-back currents in the said circuit.

4. A radio apparatus including an oscillatory circuit comprising an induction coil and a condenser, an electrostatic element surrounding and insulated from said condenser's elements, and constituting a third element of said condenser, a thermionic tube, two electrical connections from two elements of the condenser leading to the control and anode electrodes of said tube, means for regulating the flow of current in one of said connections, and a connection between the third element and the cathode.

5. A neutralizing system including an oscillatory circuit having therein the secondary of a transformer and a condenser, and an element electrostatically associated with said condenser, a thermionic tube, a grounded connection between said element and the cathode of said tube, and an adjustable connection between one plate of the condenser and the anode of the tube, the other plate of the condenser being connected to a grid of said tube.

6. In an electrical circuit having as an input circuit for a thermionic tube the secondary of a transformer and a variable condenser, an element electrostatically associated with said condenser producing a potential intermediate of potentials generated on said variable condenser and connected to the cathode of said thermionic tube, said condenser being connected to the input and anode circuits of the tube.

7. A radio apparatus including an oscillatory circuit, a thermionic tube having a cathode, a grid and a plate, one plate of the condenser in said oscillatory circuit being connected with the grid-electrode and the other plate thereof being connected with the plate-electrode of said tube through an adjustable condenser, and a grounded element electrostatically associated with, surrounding and insulated from said condenser and connected with the cathode of said tube.

8. A radio apparatus including a tuning

- circuit having therein a condenser and an associated element electrostatically related to said condenser, a thermionic tube, electrical connections from said element and one plate 5 of the condenser adapted to react on the grid circuit of the tube, and electrical connections from said element and another plate of the condenser including an adjustable condenser in the plate lead adapted to react on the plate 10 circuit of said tube.
9. A radio-frequency amplifying apparatus including a tuned circuit comprising a coil and a condenser, a thermionic tube, a plate circuit comprising the primary winding 15 of a transformer, and means to neutralize grid and plate capacity effects producing undesirable reactions between the grid and the plate circuits, said means comprising an electrode electrostatically associated with said 20 condenser and connected to a cathode of said tube, and an electrical connection between a plate of the condenser and the plate of said tube including an adjustable capacity to regulate flow of current from the plate circuit to 25 the grid circuit of said tube.
10. A radio apparatus including a thermionic relay, input and output windings associated with the control electrode and the anode of said relay, a condenser across one of
- 30 said windings, an electrostatic element inductively related to said condenser and connected to the cathode of said relay, and adjustable means to balance undesirable feed-back currents due to inter-electrode capacity of said 35 relay.
11. A radio apparatus including an oscillatory circuit, a three-electrode tube having the usual filament, grid and plate, one plate of the condenser in said oscillatory circuit being connected with the grid electrode and the other plate thereof being connected with the plate electrode of said tube through an adjustable condenser, and an element electrostatically associated with and insulated from 40 said condenser and connected with the filament of said tube.
12. A radio apparatus including a tuning circuit, a three-electrode tube having the usual filament, grid and plate, one plate of the condenser in said tuning circuit being connected with the grid electrode and the other plate thereof being connected with the plate electrode of said tube through an adjustable 45 condenser, and a third element associated with and insulated from said condenser and connected with the filament of said tube.

In testimony whereof I affix my signature.

WLADIMIR J. POLYDOROFF.
